UNITED STATES PATENT OFFICE.

CHARLES R. MILLER, OF COLLINSVILLE, TEXAS, ASSIGNOR OF FIFTY ONE-HUNDREDTHS
TO T. A. KEY, OF WHITESBORO, TEXAS.

WASHING-MACHINE.

1,200,965.

Specification of Letters Patent. Patented Oct. 10, 1916.

Application filed January 20, 1916. Serial No. 73,118.

To all whom it may concern:

Be it known that I, CHARLES R. MILLER, a citizen of the United States, residing at Collinsville, in the county of Grayson and State 5 of Texas, have invented certain new and useful Improvements in Washing-Machines, of which the following is a specification, reference being had therein to the accompanying drawing.

10 This invention relates to improvements in washing machines, one object of the invention being the provision of a machine in which the elements that act upon the clothes simulate as near as possible the rubbing action of the human, and at the same time, act upon the clothes with the least possible wear.

20 A further object of this invention is the provision of a washing machine in which two rubbing rollers are so mounted and controlled, as to permit an intermittent feeding and rubbing of the clothes being washed, this action being capable of reversal at will so that the clothes being acted upon will be thoroughly cleansed.

25 A still further object of this invention is the provision of a washing machine in which the feeding and rubbing rollers may be separated to permit the easy introduction or removal of the clothes from therebetween.

30 With the foregoing and other objects in view, the invention resides in the combination and arrangements of parts as hereafter set forth, the scope of the invention being limited only by what is claimed.

35 In the accompanying drawings:—Figure 1 is a side elevation of the complete machine taken from the operating side thereof. Fig. 2 is a front end view thereof. Fig. 3 is a vertical longitudinal sectional view through 40 the complete machine. Fig. 4 is a top plan view of the machine. Fig. 5 is a view taken from the opposite side to Fig. 1. Figs. 6 and 7 are detail views of adjacent mechanisms that controls the two rollers.

45 Referring to the drawings, the numeral
10 designates the main frame, which has
the tub bench 11, and the vertical standards
12. Carried fixedly by the upper end of the
standards 12 and extending above and par-
50 allel to the bench 11, is a frame 13, in the

outer end of which is journaled the oscillatory shaft 14, which carries thereon fixedly the roller 15, having the feeding and rubbing surface 16, which is preferably corrugated. At the ends of the shaft are provided the crank arms 17, the purpose of which will presently appear. 55

The hinges 18 support the swinging frame 19, from the upper end of the standards 12, for movement to and from the frame 13, the shaft 20 being journaled in the free end thereof, so that the roller 21 provided with the corrugated surface will be held in contact with the roller 14 therebelow. The two coiled springs 23 attached to the outer ends of the frames 13 and 19 hold the frames resiliently together, thus permitting the clothes to be washed to be accommodated between the rollers, both when being inserted and removed and during the washing thereof. 70

There are two ratchets 24 and 24' fixed upon the respective ends of the shaft 20, the teeth of one being disposed oppositely to the teeth of the other, while carried by the respective members of the frame 19, are the 75 spring held pawls 25 and 25', one of which is adapted to engage its ratchet, while the other is disengaged. To control this action of the pawls, a shaft 26 is journaled in the frame 19, and carries the two cams 27 and 80 27', which control respectively the pawls 25 and 25'. A handle 28 is connected to the shaft 26 to manually oscillate the same and selectively engage and disengage the pawls, the limiting members 29 and 29' being employed to limit the movement of the shaft 85 and thus insure the alternate action of the pawls.

As it is desired to oscillate the roller 15, a shaft 30 is journaled in the standards 12, 90 and carries upon one end the fly wheel 31, while fast to the other end is the small pinion 32, which meshes at all times with the larger drive pinion 33, journaled to the standards 11. A link 34 is connected eccentrically of the pinion 33, and is connected to the manually operable lever 35, which in turn is pivoted at 36 to one side of the frame 10. By this means the reciprocation of the lever 36 will impart rotation to the 100

shaft 30, and as the shaft 30, has fast there- to exteriorly of the frame 13, the two eccen- trics 37, the two straps 38 which fit upon and are rocked by the rotation of the eccentrics 37, and have their free ends connected to the cranks 17, will cause the lower roller 14 to be oscillated.

In order to separate the rollers to permit of the introduction and removal of the clothes from therebetween, a foot lever is pivoted at 40 to the frame 10, and is oper- ably connected through the link 41 to the frame 19 at 42. Thus by depressing the for- ward end of the foot lever, the roller 21 is elevated and the space between the two rollers increased, so that clothes may be ad- justed therebetween.

From the foregoing description taken in connection with the drawings, the operation 20 of the present washing machine is readily understood, but briefly stated it is as fol- lows: With a wash tub placed upon the bench 11 with the suds water, the foot lever 39 is depressed to separate the roller for the 25 insertion of one end of the article being washed. The foot lever is now released and the spring 23 draws the roller 21 toward the roller 14. The lever 35 is now recipro- cated and the roller 14 is first moved in the 30 direction to move the clothes a short dis- tance and through the clothes impart a slight rotation to the roller 21. As one of the pawls 25 or 25' is disengaged, and the other is engaged with its ratchet, the re- 35 verse movement of the roller 14 is a rubbing action upon the clothes, as the roller 21 is held by the pawl and ratchet from move- ment in a reverse direction. Thus this ac- 40 tion is continued until the article of apparel has nearly passed from between the rollers, at which time the operator grasps the han- dle 28 and releases the previously engaged pawl and engages the previously disengaged pawl, so that when the lever 35 is continued 45 in operation the clothes will be fed in a reverse direction. Thus by this mechanism, the clothes are intermittently moved and rubbed while stationary or nearly so, thus imitating as near as possible the hand rub- 50 bing action. This operation may be con- tinued as desired until the article is cleaned.

What I claim, as new, is:—

1. A washing machine, including a sup- porting structure, a frame secured to the 55 upper end thereof and projecting substan- tially at right angles thereto, an oscillatory feed and rubbing roller journaled in the outer end of the frame, an auxiliary frame mounted for swinging movement at the 60 upper end of the supporting structure and extending above the frame for movement to and from the frame, a second roller jour- naled in the free end of the swinging frame for movement into and out of engagement

with the first roller, mechanism for oscillat- 65 ing the first roller, means for moving the swinging frame to separate the rollers, and selective means for controlling the rotation of the second roller through the first roller, whereby clothes are intermittently 70 moved and rubbed during the passage be- tween the rollers and whereby the direction of movement of the clothes may be varied at will.

2. A washing machine, including a frame, 75 a pair of arms carried thereby at the upper end, a roller mounted in the free ends of the arms for oscillation, means for oscillat- ing said roller, a swinging frame mounted upon the frame above the arms, a second 80 roller journaled in the free end of the swing- ing frame, for movement into and out of engagement with the first roller, springs for holding the rollers resiliently together, and selective means for regulating the direction 85 of rotation imparted to the second roller, and consequently the clothes when between the rollers.

3. A washing machine, including a frame, 90 a tub bench carried thereby, an overhanging superstructure disposed above the bench and connected to the frame, a feed roller jour- naled for oscillation in the superstructure, an auxiliary frame hingedly connected to the superstructure with its free end above 95 the roller, a second roller mounted for rotation in the hinged frame, means for moving the hinged frame to engage or disengage the rollers, means for oscillating the first roller, and selective means mounted upon 100 the hinged frame for controlling the direc- tion of rotation of the second roller.

4. A washing machine, including a frame, 105 an overhanging superstructure carried thereby, an oscillatory shaft having a crank journaled in the superstructure, a roller fast to said shaft, means connected to the crank for oscillating the shaft, two arms swing- 110 ingly connected to the superstructure for movement thereabove, a second roller jour- naled in the arms for rotation, two ratchets fast to said last roller, one being the reverse of the other, two pawls, one to each ratchet mounted upon the arms, and two manually 115 operated cams connected for simultaneous movement mounted in the arms for engag- 120 ing one and disconnecting the other of the pawls, whereby as the first roller is oscil- lated the second roller is alternately rotated and halted.

5. A washing machine, including a frame 125 having an upright, two arms carried adj- acient the upper ends of the upright and at right angles thereto, a roller journaled for oscillation between the free ends of said arms, a crank connected to said roller and exterior of one of the arms, a drive shaft journaled in the upright, an eccentric

mounted thereon, a strap connecting the eccentric to the crank, two arms mounted above the first arms for movement to and from the first arms, a roller journaled in the 5 second two arms for coaction with the first roller, said rollers being held resiliently together, two oppositely disposed ratchets

connected to the last roller, a pawl for each ratchet, and means for operating said pawls, whereby one is engaged as the other is dis- 10 engaged from its ratchet.

In testimony whereof I affix my signature.

CHARLES R. MILLER.
